UNITED STATES PATENT OFFICE

CLARENCE D. ELLITHORPE, OF SPRINGFIELD GARDENS, LONG ISLAND, NEW YORK, AS-
SIGNOR TO DUPLEX ELECTRIC COMPANY, OF NEW YORK, N. Y., A CORPORATION
OF DELAWARE

METAL REFINISHER

Application filed September 30, 1930. Serial No. 485,376.

This invention relates to a portable electric machine and particularly one which is adapted to be manipulated by the hand and used for polishing and grinding and similar uses.

One of the principal objects of this invention is to provide a portable electric machine which is light and durably constructed and which may be readily carried in one hand. 10 Another object of this invention is to provide a portable electric machine which is provided with a guide strap for supporting the machine on the wrist of the operator and with projecting finger grips on the casing so 15 that the machine may be easily handled in either hand.

Another object of this invention is to provide a casing for a portable electric motor which is provided with a bevelled base so that 20 the motor may be moved along the flat surface without contacting the polishing or grinding parts and may be tipped on the bevelled edge into contact with the work to be surfaced so that the surfacing may be more 25 closely governed.

Another object of this invention is to provide a portable surfacing machine which is provided with convenient operating finger tipped control which may be operated by 30 either hand, permitting the other hand to steady or hold the work.

Another object of this invention is to provide a portable electric motor which is easily handled by one hand and which may be provided with a pistol grip so that it can be operated as a drill or similar device.

Another object of this invention is to provide a portable motor having a low speed operating shaft driven by a high speed small motor which may be adapted to receive a flexible shaft or may be operated by the pistol grip as a drill or may be used as a polishing and grinding device on its bevelled base which facilitates accurate control.

Further objects and advantages of this invention will appear from the following description thereof taken in connection with the attached drawings which illustrate preferred forms of embodiment to which my invention 45 is susceptible and in which:

Figure 1 is a side elevation of the portable machine showing the manner by which it is handled.

Figure 2 is a side elevation of the machine shown in Figure 1 showing the machine 55 tipped on the bevelled nose.

Figure 3 is a front elevation of the machine shown in Figure 1.

Figure 4 is a vertical section substantially on the lines 4-4 of Figure 3.

Figure 5 is a horizontal section substantially on the line 5-5 of Figure 1.

Figure 6 is a rear elevation with parts broken away to show the internal construction.

Figure 7 is a detail view of a modified form of driving mechanism.

The portable machine shown in Figure 1 comprises the motor casing 10 having the general shape of a flat iron having the base 12 on which the motor 14 shown in Figure 4 is mounted. A countershaft 16 extends from the front of the casing and is adapted to receive a rotatable tool 18 which will be rapidly rotated by the action of the motor 14. 70

A strap 20 extends above the casing 10 and is secured to the casing 10 by means of projecting buttons 22 which cooperate with adjustable holes 24 in the strap. The strap is adapted to pass over the wrist of the operator and the finger of the operator will grasp projecting ridges or finger grips 26 along the sides of the casing and better shown in Figure 3. As the strap is supported by the rearmost part of the casing 10 and as the finger grips 26 extend along the forward part of the casing it will be found that the machine can be very easily carried and manipulated by one hand of the operator and can be carried in either hand with equal facility.

The base 12 is provided with an upturned or bevelled nose 12a which in the normal position spaces the tool 18 above the surface of the work. When pressure of the tool on the work is desired a slight movement of the operator's wrist will raise the strap and thus the rear end of the casing to depress the shaft end as will be seen in Figure 2. In this position considerable working effect is had 100

and the pressure of the tool 18 on the work may be readily varied. The angle is relatively small and the bevel is adjacent the front end of the base. As the remainder of the base is flat the machine is easily moved along an extensive flat surface without fatigue and with a uniform result of work. If a buffer or other tool is used, however, it will be understood that the machine will be moved along the nose, thereby increasing the working pressure.

The motor is preferably mounted on the base 12 as shown in Figure 4 and is provided with a motor shaft 14a on which is mounted a gear 15 which cooperates with the gear 17 on the countershaft 16. As the normal small motor of this size revolves at an extremely high rate, it is desirable to reduce the speed for safe and convenient working conditions and the shaft 16 is preferably adapted to run at a slow speed of approximately 1200 to 1800 R. P. M. The motor is secured to the base 12 by means of a strap 19 and is mounted on suitable rubber strips or cushions 21 so that the motor may be held in a vibrationless but secure position. The inside of the motor base 12 is shown in Figure 5 and there are upstanding projections 23 to which the casing 10 is secured by means of screws or bolts 25. A toggle switch 27 is mounted on the nose or top of the front of the polisher casing in position to be operated by the forefinger of either hand of the operator to control the motor which is electrically energized through the wires 28, and switch wires (not shown).

The countershaft 16 is preferably tapped at 16a to receive a bolt 29 which secures the work wheel 18 to the countershaft 16. It will be understood that the bolt 29 is provided with threads reversed to the natural rotational movement of the countershaft so that the wheel will not come off.

The motor casing 10 is also provided with a plurality of holes 30 in the rear face of the casing and with a plurality of other holes 31 in the front of the casing for the purpose of ventilation. A fan 32 is mounted inside of the motor casing and on the motor shaft. The fan 32 thus revolves at high speed drawing air through the rear or inlet holes 30 in the casing 10 thence through the motor case and thence out through the outlet holes 31. The fan advantageously cools the motor and permits the motor to rotate at the necessary high speed without overheating.

In operation, the operator will slip his hand under the strap and grasp the casing adjacent the finger grips thus having a firm and secure hold on the polisher casing. In the common usage of this polisher, particularly on vault walls, a very large flat surface can be polished with ease and convenience and in many instances where from the nature of the work, a special equipment

would otherwise be required such as with a special graining or striping of common vault walls which have been grained, the motor may be tipped on the bevel edge and the spots on the wall and which must be removed can be effectively ground out and the surface refinished. With the present polisher and refinisher, it is possible for the operator to slide the motor along the surface of the vault wall and by first using a suitable grinding compound and appropriate brushes he can remove the spots and then with a change of work tool and the use of a suitable polishing and buffing wheel, it is possible to restore the surface to its normal condition. Normally the brush or tool is of insufficient diameter to contact directly with the work while the polisher is being slid along the surface and thus accidental cutting is avoided. The tipping of the motor brings about the results desired.

The finger grip ledges permit the machine to be held by one hand thus making it possible to use the other hand to steady the work. The motor may be controlled by a limited movement of the index finger and the toggle switch is placed in a convenient and readily accessible position which is appropriate to the fingers on either hand.

As shown in Figures 1 and 2, a pistol grip handle 35 having corrugations 36 to engage the fingers may be mounted on a stud 37 on the extreme end of the casing 10. A suitable nut 38 is adapted to tighten the pistol grip 35 and also permits relative rotation of the pistol grip about the stud 37. The pistol grip is sometimes desirable where the motor is used in an inaccessible position and when it is inconvenient to support the motor by the strap 20. It may also be used when additional force is required to force the work tool into contact with the work to be cleaned. The handle may be removed or rotated about the stud 37 as desired.

As shown in Figure 7, the motor may be used as a source of power for a flexible shaft 40 and hand operated tool 46. The flexible shaft 40 is provided with a securing bracket 42 which is mounted on the front end of the housing 10 by means of the screw 44. The power shaft is provided with a screw threaded end 45 which engages and screws into the tapped end 16a of the shaft 16. A manually controlled handle 46 may be provided for the work end of the shaft 40 and the work tool 18 may be secured to the end of the flexible shaft in any well known manner.

With such a construction it is also possible and convenient to handle the polisher and casing in one hand with the finger adjacent the controlling toggle switch 27 and leave the other hand free to manipulate the handle 46 adjacent the work tool. This tool may be a buffer, grinder, brush or drill or other device and due to the gearing, sufficient torque

is available to operate such devices. Although the device is particularly desirable for purposes of cleaning and restoring the original grained finish of vault doors leaving the door with the original bright appearance, it is also equally as well adapted for buffing or polishing flat or round surfaces and with the extension shaft is adapted to reach otherwise inaccessible places with the same convenience as when carried in the hand.

The polisher is light, compact, and sturdy and easily carried on the wrist for long periods without fatigue. The strap on the rear of the casing gives good leverage to enable the motor to be raised onto the bevel thus forcing the work tool into contact with the surface to be refinished. Various tools may be used as the nature of the work requires and for inaccessible places or drilling, the flexible shaft is highly efficient.

While I have shown a preferred form of embodiment of my device, I am aware that other modifications may be made thereto and I therefore desire a broad interpretation of this invention within the scope and spirit of the description thereof and the claim appended hereinafter.

I claim:

A portable tool of the class described comprising a flat iron shaped casing having a forwardly bevelled base, a motor in said casing, a motor shaft projecting from the front end of said casing, gripping ledges along each side of said casing, a supporting member mounted on the rear of the casing, means to ventilate said motor comprising a fan on the motor shaft and ventilating openings in said casing, and a toggle switch adjacent the front of said casing adapted to be manipulated by the operator's finger, said supporting member extending over the operator's hand whereby said tool may be tipped on said beveled base and a pistol grip to facilitate such movement.

In testimony whereof I have affixed my signature to this specification.

CLARENCE D. ELLITHORPE.
